UNITED STATES PATENT OFFICE.

ALBERT ILLIAS, OF NEWARK, NEW JERSEY, ASSIGNOR OF ONE-HALF TO CARL SCHMIDT, OF NEWARK, NEW JERSEY.

VALVE-COOLING DEVICE.

1,294,911.

Specification of Letters Patent. Patented Feb. 18, 1919.

Application filed September 10, 1918. Serial No. 253,432.

To all whom it may concern:

Be it known that I, ALBERT ILLIAS, a subject of the King of Hungary, and a resident of Newark, in the county of Essex and State of New Jersey, have invented certain new and useful Improvements in Valve-Cooling Devices, of which the following is a specification.

The present invention relates to means for cooling the exhaust valves of internal combustion engines; and has for its main object to utilize for this purpose the combustible mixture as the same enters the cylinder of the engine.

Another object of the invention is to provide a simple and efficient construction, that can be applied to engines without necessitating material changes in the construction thereof.

A further object of the invention is to so devise the cooling device that it serves at the same time as a means for pre-heating the combustible charges.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction, within the scope of the appended claims, without departing from the spirit or sacrificing any of the advantages of the invention.

One of the many possible embodiments of the invention is illustrated in the accompanying drawings, in which:—

Figure 1 is a vertical section taken through the combustion chamber of an internal combustion engine having the improved cooling device therein; Fig. 2 is a side elevation of the cooling means; Fig. 3 is a top plan view thereof; and Fig. 4 a section taken through an improved exhaust valve of the engine.

In the drawings, the numeral 10 indicates the working cylinder of an internal combustion engine, including a combustion chamber 11, having the usual igniting device 12. The chamber 11 is provided with an intake 13 for the combustible mixture, and with

an exhaust opening 14 for the products of combustion or exhaust gases. The intake is controlled by a supply-valve 15 of any suitable construction, that is disposed within a tubular body 16, communicating with the intake. This body is provided with seat 17 for the supply-valve, and extends toward 60 and terminates above the exhaust-valve 18, that controls the exhaust opening.

The exhaust-valve, is made in the form of a puppet, comprising a disk 19 and a stem 20. The disk is provided with an upwardly extending peripheral flange 21, through which extend small apertures 22. The inner diameter of the flange 21 is substantially larger than the outer diameter of the downwardly directed free end of the tubular body, so as not to interfere with the proper operation of the exhaust-valve.

The tubular body 16 is made of two sections, denoted in the drawings by the numerals 24 and 25, which are detachably united by a screw 26 or other suitable means. The length of the section 24 is such, that convenient access can be had to the exhaust-valve after the section 25 has been detached from the section 24. In registering 80 position with the supply-valve is formed in the section 24 of the tubular body an opening 27, normally closed by a plug 28. The diameter of the opening 27 is larger than that of the disk 15 of the supply valve. 85

The operation of the cooling device is as follows:—The combustible mixture enters through the intake 13 the tubular body 16, flows through the same and is directed by the downwardly bent discharge end of said 90 body onto the exhaust valve 18. Part of the charge is thrown off or back by the disk 19 of said valve and part flows through the apertures 22 in the flange 21 thereof, thereby effectively cooling the valve.

The combustible mixture, in cooling the exhaust valve, is pre-heated for the well-known purpose. The device has thus a two-fold function, towit: First, it serves as a cooler for the exhaust-valve of the engine, 100 and, second, it pre-heats the fresh charge.

When it becomes necessary to re-grind the valve seats, the cylinder head 29 is removed from the cylinder, after which the section 25 of the tubular body 16 is detached from 105 the section 24 thereof, whereby access can be

had to the exhaust-valve. In order to reach the supply-valve, the plug 28 is unscrewed from the section 24 of the tubular body.

What I claim is:—

- 5 1. An internal combustion engine including a cylinder having an intake-opening and an exhaust-opening, a valve controlling said intake-opening, a valve controlling said exhaust-opening, each valve being provided with a stem and the longitudinal axes of said stems being spaced apart, and a tubular body communicating with said intake opening inclosing said intake-valve and leading to and terminating above said exhaust-valve.
- 10 2. An internal combustion engine including a cylinder having an intake-opening and an exhaust-opening, a valve controlling said intake-opening, a valve controlling said exhaust-opening, each valve being provided with a stem and the longitudinal axes of said stems being spaced apart, and a tubular body communicating with said intake-opening and leading to and terminating above said exhaust-valve.
- 15 3. An internal combustion engine including a cylinder having an intake-opening and an exhaust-opening, a valve controlling said intake-opening, a valve controlling said exhaust-opening; each valve being provided with a stem and the longitudinal axes of said stems being spaced apart, and a tubular body communicating with said intake-opening and having its discharge end in proximity of but spaced from said exhaust-valve.
- 20 4. An internal combustion engine including a cylinder having an intake-opening and an exhaust-opening, a valve controlling said intake-opening, a valve controlling said exhaust-opening, each valve being provided

with a stem and the longitudinal axes of 40 said stems being spaced apart, and a tubular body communicating with said intake-opening and inclosing said intake-valve and having its discharge end in proximity of but spaced from said exhaust-valve.

45 5. An internal combustion engine including a cylinder having an intake-opening and an exhaust opening, a valve controlling said intake-opening, a valve controlling said exhaust-opening including a disk having an 50 upwardly extending peripheral flange provided with apertures, and a tubular body communicating with said intake-opening and leading to and terminating above said exhaust-valve, whereby part of the charge 55 flows through the apertures in the flange of said exhaust-valve.

6. An internal combustion engine including a cylinder having an intake-opening and an exhaust-opening, a valve controlling said 60 intake-opening, a valve controlling said exhaust opening including a disk having an upwardly extending peripheral flange provided with apertures, and a tubular body 65 communicating with said intake-opening inclosing said intake-valve and leading to and terminating above said exhaust-valve, whereby part of the charge flows through the apertures in the flange of said exhaust-valve.

70 Signed at New York, in the county of New York and State of New York, this 17th day of July, A. D. 1918.

ALBERT ILLIAS.

Witnesses:

CARL SCHMIDT,
SIGMUND HERZOG.
